MULTIPLE STUDY CARREL UNIT

Charles E. Ball, Buffalo, N.Y., assignor to Clarin Mfg. Co.,
Chicago, Ill., a corporation of Illinois

Filed Sept. 22, 1966, Ser. No. 3,972

Term of patent 14 years

(Cl. D33—11)

FIG. 1

FIG. 2

FIG. 3FIG. 4FIGURE 1 is a perspective view of a multiple study carrel unit embodying my new design;

FIGURE 2 is a front elevational view thereof;

FIGURE 3 is a top plan view thereof; and

FIGURE 4 is an end elevational view thereof, taken from the left of FIGURE 2.

The dominant features of my design are shown in solid lines.

The back and the side not shown are plain and unornamented.

I claim:

The ornamental design for a multiple study carrel unit, as shown and described.
